LAPPING AND HONING MACHINE

William Arthur Oubridge, Coventry, England

Application May 4, 1934, Serial No. 723,981
In Great Britain May 8, 1933

10 Claims. (Cl. 51—118)

This invention relates to lapping and honing machines of the type comprising a pair of relatively rotatable laps between which the work is carried by means of a cage or holder, and has 5 for its object to provide improved means for moving one of the laps towards and away from the other for the purpose of enabling the work to be placed in and removed from the said holder or cage, and for regulating the pressure between 10 the laps.

According to the present invention the separation of the two laps and the control of the pressure between them is effected by pneumatic means involving the provision in association with 15 the spindle of one of said laps of the plunger or piston of a cylinder connected with a supply of air or gas under pressure controlled by appropriate valve mechanism.

The invention also includes a new or improved 20 construction of the machine as a whole in which the mechanism controlling the rotary and axial movements of the upper lap is located below the bottom lap, the spindle of the former passing downwardly through the centre of the latter.

In the accompanying drawings,

Figure 1 is a vertical sectional view of the 25 improved lapping machine.

Figure 2 is a view in front elevation thereof.

Figure 3 is a plan.

Figure 4 is a sectional view of one form of 30 control valve.

Figure 5 is a diagrammatic view showing an alternate form of valve and its connections with the cylinder.

In the drawings, the invention is shown as 35 applied to a lapping machine in which the upper lap 2 is supported and operated from below, but the means employed for separating the laps is not necessarily limited in its application to this 40 type as it can obviously be applied to machines in which the upper lap is supported and operated from above.

In the construction shown the upper lap 2 is fixed to a spindle 3 which protrudes vertically 45 through the centre of the lower lap 4 and is rotatably mounted in bearings 5 of substantial length in a tubular spindle 6 to a flange 7 on which the lower lap is firmly secured by bolts 8. The tubular spindle 6 is itself rotatably 50 mounted in upper and lower bearings 9 in a central tubular member 10 of the bed or frame 11 of the machine.

The two laps are rotated simultaneously and 55 in opposite directions from a horizontal shaft 12 which is mounted in bearings 13 carried by

the frame of the machine. One end of this shaft carries a pair of bevel pinions 14, 15 keyed thereto, said pinions meshing respectively with oppositely arranged bevel wheels 16, 17. One of these bevel wheels 16 is fixed to the lower end of the 5 tubular spindle 6 whilst the other 17 is rotatably mounted in a bearing 18 supported by the frame of the machine, and is in driving engagement with the splined lower end of the spindle 3 which is free to slide axially through it.

The driving shaft 12 is driven by a belt pulley 19 which is free to rotate thereon and carries one member 20 of a clutch the other member 21 of which is keyed to the outer end of said shaft and carries a split band 22 adapted to be 15 expanded into frictional engagement with the first member by means of a cam 23 the lever 24 of which is operated by a sliding collar 25 having a conical end 26. The said collar is moved into and out of its operative position by means 20 of a hand lever 27, Figure 2, mounted at the other side of the machine and connected by a bar 28 to a crank 29 on a short spindle 30 the other end of which carries a striking fork 31 25 engaging a groove 32 in said collar.

The raising of the upper lap by pneumatic power is effected by means of a plunger 33 working in a cylinder 34 fixed to the machine frame. The plunger rod is pivotally connected by means of a cross-head 35 with the end of a lever 36 30 which is pivoted at 37 in the frame 11 and at an intermediate part is pivotally connected with the lower end of the spindle 3 by means of a block 38 carrying ball thrust bearings 39.

The supply of compressed air to the working 35 cylinder is controlled by means of a valve 40 by turning which in the appropriate direction the interior of the cylinder below or above the plunger is placed in communication with the air supply.

In its simple form, represented in Figure 5, the valve 40 which may be conveniently arranged at the front of the machine as shown in Figure 2 and is of the rotary plug type, has three ports, viz: an inlet port 41 communicating with a supply of compressed air or gas, a cylinder port 42 communicating with the lower end of the cylinder 34, and an exhaust port 43. In this case the valve plug has a single transverse passage 44. When the valve is turned to the position shown, 45 compressed air enters the cylinder through the pipe 45 below the plunger causing the latter to raise the lever 36 and thereby lift the upper lap 2 clear of the bottom lap, the splined lower end of the spindle 3 sliding through the bevel 50

wheel 17. The upper lap is maintained in the raised position by the air pressure so long as the valve remains open. When the valve is closed to inlet and opened to exhaust the upper lap is 5 free to descend, its downward movement being controlled by the area of the exhaust port which may be varied by adjustment of a cock 46 so that as the upper lap, in descending, approaches the lower lap its movement is cushioned and 10 slowed down.

Where it is desired to increase the pressure on the work beyond that due to the dead weight of the upper lap the valve may, as shown in Figure 4, be provided with an additional cylinder port 15 47 communicating with the upper end of the cylinder 34. In this case the valve plug would have two transverse passages, 44 and 48, one which establishes communication between the inlet port 41 and one end of the cylinder whilst the other 20 establishes communication between the other end of the cylinder and the exhaust port 43.

The raising of the upper lap 2 is assisted by means of counterweights 49 which are attached to an adjustable fitting 50 on the lever 36 by 25 cables 51 passing over guide pulleys 52. The purchase of the weights on the lever can be varied as the weight of the upper lap decreases with wear by adjusting the fitting 50 along the lever. For this purpose the said fitting is formed 30 with a tapped hole 53 to receive the screw-threaded end of an axially immovable spindle 54 mounted rotatably in the lever and having its outer end 55 adapted to receive a key whereby the spindle can be rotated.

35 The form of the work-holder will vary with the nature of the work to be lapped or honed. For the purpose of lapping piston rings, for example, the said holder consists of a circular plate 56 arranged between the laps and formed with a 40 number of circular openings (not shown) to receive the rings. At positions approximately 90° apart a pair of lugs 57 are secured to the holder and these serve to connect the holder with a pair of crank pins 58. The spindle 59 of each crank 45 pin has secured to it a sprocket wheel 60 and these are driven from a sprocket 61 on the spindle 6 of the lower lap by means of an endless chain 62. By means of the crank pins the work-holder is given a circular motion between the laps. The crank spindles are mounted outside 50 the pan 63 surrounding the lower lap so that the actuating mechanism for the holder is clear of the abrasive liquid in the pan.

55 The abrasive liquid is supplied to the laps from a container 64 mounted upon the carrier plate 65 of the upper lap 2 and flows between the laps into the aforesaid pan 63 surrounding the lower lap, being returned to said container through a pipe 66 by means of a pump which is not shown.

60 In order to prevent the abrasive liquid finding its way from the lower lap to the upper spindle bearing 5, when the machine is running with the upper lap in its operative position, the position of the upper end of the said bearing is such 65 that, however much the lower lap 4 may be flooded, it is impossible for the liquid to reach and impair the efficiency of the said bearing. For this purpose the tubular spindle 6 is extended or raised so that its upper end projects an appreciable distance above the normal level of the liquid in the said container when the upper lap is lowered onto the bottom lap. As an additional precaution tubular baffles 67, 68 are fitted between the upper bearing 5 and the cap 69 which 70 closes the upper end of the spindle 3, said baffles 75

telescoping with each other, one, 67, being fixed to the carrier plate 10 of the lower lap 4 and the other, 68, to the carrier plate 65 of the upper lap. The arrangement is such that before any of the liquid can possibly reach the bearing it 5 must pass over the upper edge of the outer baffle 68 down between the two baffles and up again to the bearing 5. Incidentally, the raising or extension of the tubular spindle has the further important advantage that it provides a better 10 support for the spindle 3 of the upper lap against the stresses set up by the rotary movement of the latter.

It will be understood that during the lapping or honing operation the permissible amount of 15 material to be removed from the work is extremely small and some provision is therefore desirable for enabling the operator to know when the operation should be stopped. For this purpose there is associated with the upper lap 2 20 a lever 70 which is pivoted to a fixed part of the machine, such as the adjustable pillar 71 on the pan 63, and rests freely upon a stud in the cap 69. When the upper lap is lowered into its operative position with respect to the lower lap 4, the free end of this lever enters the forked upper end 72 of a stationary pillar 73 where it makes contact with the plunger 74 of a gauge 25 75 mounted upon said pillar. As the lapping or honing operation proceeds the upper lap, being 30 free axially, adjusts itself to the work and this movement is magnified at the free end of the lever where it makes contact with the plunger of the gauge. By this means an extremely fine reduction, such as a fraction of one thousandths 35 part of an inch will show as a readily visible reading on the gauge so that the operator can work within very fine limits.

I claim:—

1. A lapping and honing machine of the character described comprising a pair of relatively rotatable superposed laps, means for causing rotation of said laps, a work-holder located between said laps, and means extending through the rotational centers of both of said laps, said means being connected to one of said laps and being adapted to have movement in an axial direction with relation to the other of said laps to cause movement of the former lap in an axial direction with relation to said other lap. 40

2. A lapping and honing machine of the character described comprising a pair of relatively rotatable superposed laps, a work-holder located between said laps, means operating through the rotational center of the lower lap for moving the upper lap relatively to the lower lap along the axis of rotation, and means arranged below said laps for imparting relative rotary movement thereto. 55

3. A lapping and honing machine of the character described comprising a pair of relatively rotatable superposed laps, a work-holder therebetween, and power-operated means arranged below the laps and operating through the rotational center of the lower lap for moving the upper lap axially relatively to the lower lap. 60

4. A lapping and honing machine of the character described comprising a pair of superposed laps, a work-holder located between them, a 70 rotatable tubular spindle carrying one of said laps, an inner rotatable spindle mounted in said tubular spindle and carrying the other lap, and power operated means for imparting relative axial movement to said spindles. 75

5. A lapping and honing machine of the character described comprising a pair of superposed laps, a work-holder located between them, a rotatable tubular spindle carrying one of said laps, an inner rotatable spindle mounted in said tubular spindle and carrying the other lap, a lever connected with the spindle of one of said laps and means associated with said lever for separating said laps. 10
- 10 6. A lapping and honing machine of the character described comprising a pair of superposed laps, a work-holder located between them, a rotatable tubular spindle carrying one of said laps, an inner rotatable spindle mounted in said tubular spindle and carrying the other lap, a cylinder, a plunger working therein, a lever connected with said plunger and with the spindle of one of said laps and means for controlling a supply of compressed air or gas to said cylinder. 15
- 15 7. A lapping and honing machine of the character described comprising upper and lower rotatable laps, a work-holder therebetween, means for moving one lap relatively to the other in the direction of the axis of rotation, a tubular spindle for the lower lap extending through and above the upper lap when the latter is in its operative position with respect to the lower lap, a central spindle mounted in said tubular spindle and carrying the upper lap, and means common to both spindles arranged below the lower lap for rotating said spindles at different speeds. 20
- 20 8. A lapping and honing machine of the character described comprising a lower lap, an upper lap, an abrasive liquid container carried by said upper lap, a tubular spindle for the lower lap extending above the normal level of the liquid 25
- 25 in said container, a central spindle mounted in said tubular spindle and carrying said upper lap, a driving shaft arranged below the lower lap and adapted to impart relative rotary movement to said spindles and laps, a bearing in the upper end of said tubular spindle for said central spindle, and means associated with the upper and lower laps and adapted to co-operate together to prevent access of said abrasive liquid to said bearing. 30
- 30 9. A lapping and honing machine of the character described comprising a lower lap, an axially free upper lap adapted to co-operate therewith, a work-holder located between said laps, driving mechanism operating from below said laps for imparting relative rotary movement thereto, power-operated means for separating said laps, and means associated with said upper lap for measuring the extent of its axial displacement consequent upon each lapping or honing operation. 35
- 35 10. A lapping and honing machine of the character described comprising a lower lap, an axially free upper lap superposed thereon, a work-holder located between said laps, means operating through the rotational center of the lower lap for moving the upper lap relatively to the lower lap along the axis of rotation, driving mechanism for imparting relative rotary movement to said laps, a lever responsive to axial movement of said upper lap and a gauge associated with said lever for measuring and indicating the extent of the axial displacement of said upper lap consequent upon each lapping or honing operation. 40

WILLIAM ARTHUR OUBRIDGE.
